John E. Prager,
ATTORNEY

UNITED STATES PATENT OFFICE

SIMON WOLF, OF BRONX, NEW YORK

COLLAPSIBLE DRESS FORM

Application filed August 27, 1931. Serial No. 559,697.

This invention relates to apparatus used by dress makers, tailors, and clothiers for the display of wearing apparel, and also as a form during fitting and shaping of a garment, such devices being known as dummies.

Ordinarily the form is a hollow molded figure of papier-maché or similar material, conformable with the shape of the upper portion of a human figure, including such parts as the breast, shoulders, neck, back, and waist, with a skirt outline therebelow formed of bent wires, this structure being usually encased in cloth permitting pinning a garment to it while being fitted.

As the garment is commonly stripped off the form at its top and the waist portion of the form generally has a circumference smaller than the shoulders, and because of this difference in circumference a provision is made for decreasing the circumference of the bust and shoulders, so that the garment is readily removable without the usual slit necessary in the waist of the garment.

It is therefore an object of this invention to provide a form having a gracefully shaped waist and contractile shoulders to permit movement of a garment thereover.

A further feature is in the provision of a form having resiliently spread shoulders to fit any garment suited to the size of the form, and means to contract the shoulders when it is desired.

Another purpose is to produce an improved form, readily adjusted by the foot of an operator, leaving the hands free for other work.

These advantageous objects are accomplished by the novel construction and combination of parts hereinafter described and illustrated in the accompanying drawing, forming a material part of this disclosure, and in which:—

Figure 1 is a perspective view of an embodiment of the invention looking from the front.

Figure 2 is a side elevational view of the same as mounted on a stand.

Figure 3 is a partial longitudinal section-al view showing operative parts of the structure.

Figure 4 is a diagrammatic view illustrating the variable positions of the shoulders.

Figure 5 is a fragmentary rear view, partly in section, of the lower part of the adjusting means.

The form stand comprises a post 10 fixed in a base 11 provided with gliders for convenience in moving over a level surface, the upper end of the post being fixed in a platform 12 constituting the lower end of the form, the same being shaped in profile to suit.

Erected on the platform are the frame walls 14 of the form, shaped conformable with a person's figure, and terminating at the top in a neck provided with a cap 15 having a handle 16.

The several parts of the form body are covered with a woven textile fabric casing 17, from below the cap to the platform, to which the material being fashioned into a garment may be temporarily held by pins which may also be entered into the frame 14.

Below the platform may be wires 18 bent to retain a skirt in position; all these several parts are old and well known, forming no part of the present invention, but illustrating its application.

In the present case the sides of the frame body are omitted at points adjacently surrounding the shoulders and extending almost to the waist, as at 20—20', respectively top and bottom of the openings, and fitted to these openings are substitute frame elements 21, having cloth coverings 22.

These elements are connected at their lower edges to the main frame by flexible hinges 23, such as thin leather, suitable fabric or metal, and the upper, inreaching portions 21' of the insert elements 21, at the top of the shoulders, are shaped and adapted to be moved inwardly, under the rigid main frame portions adjacent.

Fixed on the exteriors of the hinged frame sections, in a position corresponding to the arms, are convex metallic caps 24 providing an ornamental finish.

A block 25 is secured on the form frame rear wall, closely below the neck, this block

having mounted in it a spindle 26 on which are a pair of pulleys 27 having cords 28 trained over them, their upper portions being oppositely directed, extended through 5 the walls of the hinged elements 21 and engaged with eyes fixed on the inner sides of the caps 24.

The cords also pass through openings in corner blocks 30 used to reinforce the 10 hinged elements 21 and which are normally thrust outwardly by coiled compression springs 31 encircling the cords and having their ends disposed in recesses in the blocks 25 and 30 respectively, whereby the hinged 15 elements are pressed outwardly.

The down-reaching ends of the cords 28 are attached to the upper end of a plunger bar 32 slideable through the platform 12 and to which is rigidly secured a tubular guide 20 34, having a longitudinal slot 35 and engaged by a clamp 36 having forks which are 35 slidably guided by the post 10.

Fixed in the lower portion of the plunger bar 32 is an arm 37 carrying at its outer end 25 a pedal 38 adapted to be depressed by the foot of an operator, thereby drawing the cords against the effect of the springs 31, causing retraction of the hinged frame elements representing the shoulders, this condition being apparent in Figure 4.

If it be desired to retain the shoulders in their retracted position, the arm 37 may be moved in the slot 35 and turned to one side to engage under an abutment 39 formed on 35 the guide 34, as best seen in Figure 5.

From the foregoing it will be seen that a simple device for this purpose has been disclosed in the preferred form of its embodiment, but it is not desired to restrict the details to the exact construction shown, it being obvious that changes, not involving the exercise of invention, may be made without conflicting with the scope of the appended claims.

Having thus described the invention, what is claimed as new and desired to secure by Letters Patent is:—

1. In a dress form, a body having openings at the shoulders, closures for the openings, hinges connecting said closures at their bottoms to said body and resilient means to normally press said closures outwardly.

2. In a dress form, a body having openings extending from the shoulders to the waist, closures hinged at their lower ends to swing inwardly, and resilient means to press the closures outwardly.

3. In a dress form, a body having openings 60 extending from the shoulders to the waist, closures hinged at their lower ends to swing inwardly, re-enforcing blocks at the inner corners of said closures, a block fixed in said body intermediate the closure carried 65 blocks, and compression springs intervening

said blocks to press the closures outwardly.

4. In a dress form, a body having openings extending from the shoulders to the waist, closures hinged at their lower ends to swing inwardly, re-enforcing blocks at the inner corners of said closures, a block fixed in said body intermediate the closure carried blocks, compression springs intervening said blocks to press the closures outwardly, and means to retract said closures. 70

5. In a dress form, a body having openings extending from the shoulders to the waist, closures hinged at their lower ends to swing inwardly, re-enforcing blocks at the inner corners of said closures, a block fixed in said body intermediate the closure carried blocks, compression springs intervening said blocks to press the closures outwardly, a pair of cords to retract said closures, and pedal means to operate said cords. 75

6. A dress form having retractable shoulder portions, a block fixed in said form intermediate the shoulders, compression springs between the shoulder portions and block, pulleys mounted in said block, cords fixed to said shoulder portions to extend over said pulleys, a plunger rod to which the inner ends of said cords are attached, a guide for said rod, a pedal fixed on said rod, and means to hold said pedal when in a lowered position. 80

7. A dress form having retractable shoulder portions, hinged to fold inwardly, caps on said shoulders, reinforcements fixed on the inner sides of the shoulders, a block fixed in said form between the shoulders, compression springs extending between said reinforcements and block, pulleys mounted in said block, a pair of cords trained over said pulley having their outer ends engaged with said caps and their lower ends extending downward, a plunger rod to which the lower ends of said cords are attached, a tubular guide for said rods, said guide being slotted, an arm fixed in said plunger, said arm having a pedal at its end, and means combined with said arm to retain said shoulders when in a retracted position. 85

8. In a dress form, a body having contractible shoulder elements, compression springs urging said elements outwardly and pedal actuated means for retracting said elements. 90

In testimony whereof I affix my signature. 120
SIMON WOLF.
